Law Office LLC(57) **CLAIM**

The ornamental design for a tissue box holder, as shown and described.

DESCRIPTION

FIG. 1 is a top perspective view of a tissue box holder showing our new design;

FIG. 2 is a right side elevational view of the tissue box holder in FIG. 1;

FIG. 3 is a left side elevational view thereof;

FIG. 4 is a front elevational view thereof;

FIG. 5 is a rear elevational view thereof;

FIG. 6 is a top plan view thereof; and,

FIG. 7 is a bottom plan view thereof.

The ornamental design which is claimed is shown in solid lines in the drawings. The broken lines form no part of the claimed design.

1 Claim, 7 Drawing Sheets(56)
